UNITED STATES PATENT OFFICE.

HENRY C. BARKER, OF SEDALIA, MISSOURI.

BRICK-MACHINE.

SPECIFICATION forming part of Letters Patent No. 274,700, dated March 27, 1883.

Application filed December 23, 1882. (No model.)

To all whom it may concern:

Be it known that I, HENRY C. BARKER, of Sedalia, in the county of Pettis and State of Missouri, have invented certain new and useful 5 Improvements in Brick-Machines; and I do hereby declare that the following is a full, clear, and exact description of the invention, which will enable others skilled in the art to which it appertains to make and use the same, 10 reference being had to the accompanying drawings, which form a part of this specification, and in which—

Figure 1 is a side view of my improved brick-machine, and Fig. 2 is a similar view from the 15 other side.

Similar letters of reference indicate corresponding parts in both the figures.

My invention has relation to machines for 20 pressing dry clay into bricks; and it consists in the improved construction and combination of parts of the same, as hereinafter more fully described and claimed.

In the accompanying drawings, the letter A indicates the table of the machine, which has 25 a recess, B, in which the presser-blocks C and D move, forming the mold. These blocks slide between two uprights, E, and are guided by rollers F and G, extending into grooves H in the uprights. In the ends of block C, and opening inward, is a recess, I, into which extends the end of a lever, J, having a roller, K, and pivoted upon uprights E in a bearing, L. The lower block, D, has a recess, M, in the lower rear corner, which opens to the rear and downward, into which the end of a lever, N, having a roller, O, and pivoted in a bearing, P, extends. The ends of levers J and N are hinged to two toggles, Q, which are hinged to a head, R, sliding in guides S, and hinged to a pitman, T. This pitman T has a slotted head, U, in which slides a wrist-pin, V, fastened upon the rim of a cog-wheel, W, which derives its motion from a pinion, X.

The clay is fed from a hopper, Y, into the 45 feeder a, which slides under the hopper upon the table A. A short arm, b, is hinged to the rear end of the feeder, and a lever, c, is hinged to the said arm. This lever is pivoted in a bearing, d, upon a brace, e, of the frame, and an arm, f, having a projection, g, in its other end, and sliding in bearings h, is hinged to its

lower end. Upon the face of the rim of cog-wheel W is a projecting roller, i, which engages projection g once in every revolution, drawing it back, which motion causes lever c 55 to push the feeder forward. The feeder is drawn back by a projecting roller, j, on the wheel W, engaging one end of a lever, k, pivoted at l, and connected to lever c by an arm, m. The projecting roller j engages also part 60 of a lever, n, which is pivoted in a bearing, o, and the upper part, p, of which is curved in toward the wheel, so as to enable roller j to reach it and engage it.

To the lower end of lever n is hinged an 65 arm, q, which is hinged to the one arm r of a bell-crank, pivoted at s, the curved arm t of which passes under the roller G, lifting it and the lower presser-block when the arm r is drawn back.

The operation of the machine will be easily understood by the foregoing description taken in connection with the accompanying drawings. The dry clay is fed from the hopper into the opening Z in the feeder. The feeder is 75 brought forward and drops the clay into recess B upon blocks D, at the same time pushing the last brick forward. The feeder is thereupon drawn back, the toggles Q straightened, and the blocks pressed together, forming a 80 brick. As the toggles are bent the upper block is raised, and the roller O upon lever N is lowered; but roller j, pressing upon lever n, operates the bell-crank r t and raises the lower block flush with the table, when the 85 feeder slides forward, pushing the finished brick forward, and depositing its load after block D is dropped. In sliding forward, block C is tilted forward, swinging upon rollers F.

It will be seen that by the pitman T having 90 slotted head U it will allow the wheel W to turn for a short space of time without operating the toggles, in which time the projections operate the feeder and the lever, which lifts the lower block.

Having thus described my invention, I claim and desire to secure by Letters Patent of the United States—

1. In a machine for pressing bricks, the upper plunger, C, having rollers F, sliding in grooves H in uprights E, and recess I, for the reception of the end of the operating-lever, and lower

plunger, D, having rollers G sliding in grooves H and recess M, substantially as shown and set forth.

2. The combination of the plungers C and D, having rollers F and G and recesses I and M, with levers J and N, having rollers K and O, bell-crank r t, and means for operating them, substantially as shown and set forth.

3. The combination of the plungers C and D, having recesses I and M, levers J and N, having rollers K and O, toggles Q, cross-head R, sliding in guides S, pitman T, having slotted head U, and wheel W, having wrist-pin V, substantially as set forth.

4. The combination of the plungers C and D, levers J and N, toggles Q, cross-head R, pitman T, having slotted head U and wheel W, having wrist-pin V, with the feed and discharge slide a, and bell-crank r t, and means for operating them, substantially as shown and set forth.

5. The combination of the feed and discharge slide a, arm b, lever c, arm m, lever k, arm f, having projection g and wheel W, having projecting rollers i and j, with the plungers C and D and means for operating them, substantially as shown and set forth.

6. The combination of the lower plunger, D, having recess M and roller G, and means for operating it, bell-crank r t, arm q, lever n, and wheel W, having projection j, with plunger C and means for operating it, and feed and discharge-slide a and means for operating it, substantially as shown and set forth. 30

7. The combination of the table A, having recess B and uprights E, having grooves H, plunger C, having recess I and roller F, plunger D, having recess M and roller G, levers J and N, having rollers K and O, toggles Q, cross-head R, guide S, pitman T, having slotted head U, wheel W, wheel X, feed and discharge slide a, arm b, lever c, arm m, lever k, arm f, having projection g, bent lever n, arm q, and bell-crank r t, substantially as and for the purpose shown and set forth. 35 40 45

In testimony that I claim the foregoing as my own I have hereunto affixed my signature in presence of two witnesses.

HENRY C. BARKER.
